UNITED STATES PATENT OFFICE.

LAURENCE E. TOPHAM, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

EDGE-SETTING MACHINE

Application filed August 24, 1920, Serial No. 405,605. Renewed October 20, 1926.

This invention relates to shoe machines and more particularly to machines for operating upon shoes of the type in which the shoe and the means for operating upon the shoe are moved relatively to transfer the point of operation about the shoe and in which mechanism is provided for relatively moving the operating means and the shoe to maintain the operating means and the shoe in the proper relative positions at the point of operation as such point is transferred about the shoe.

The several features of the invention are intended primarily for use in machines in which the shoe is supported in operating position in the machine and all of its movements are effected and controlled by automatically acting mechanisms. Certain features of the invention, however, are not limited to machines which are wholly automatic. Also certain features of the invention may be embodied with advantage in machines for operating upon shoes in which the shoe is held and manipulated by the operator.

The principal object of the present invention is to produce a machine of the type first above referred to which is adapted to perform the operation of setting the edge of a shoe sole.

Another object of the invention is to produce a machine of the type first above referred to which is adapted to perform in a satisfactory manner the operation of edge setting on a shoe, the sole edge of which has a shape about the forepart different from the shape along the shank.

Another object of the invention is to improve the construction and mode of operation of shoe machines in which two different tools are employed to operate successively along different parts of a shoe bottom.

Other objects of the invention are to improve the construction, arrangement and mode of operation of various parts of edge setting machines.

With the above objects in view, the present invention consists in the combinations, constructions and arrangements of parts hereinafter described and claimed, the advantages of which will be obvious to those skilled in the art from the following de-

scription taken in connection with the accompanying drawings illustrating the several features of the present invention in their preferred form.

In the drawings Fig. 1 is a view in front elevation of a machine embodying the invention; Fig. 2 is a view in front elevation of the edge setting head of the machine; Fig. 3 is a view in side elevation of the edge setting head looking from the right; Fig. 4 is a view similar to Fig. 3 with certain of the parts in different positions; Fig. 5 is a view in vertical section of a portion of the edge setting head taken substantially on the line 5—5 of Fig. 6; Fig. 6 is a view in horizontal section of a portion of the edge setting head taken substantially on the line 6—6 of Fig. 5; Fig. 7 is a detail view illustrating the carrier for the edge setting tools and the upper tool mounted thereon; Fig. 8 is a detail sectional view taken substantially on the line 8—8 of Fig. 5; Fig. 9 is a detail sectional view taken substantially on the line 9—9 of Fig. 5; Fig. 10 is a view in side elevation partly in section illustrating the parts in the lower portion or base of the machine; Fig. 11 is a detail view in plan illustrating the mechanism for actuating the jack to impart feeding movements to the shoe; Fig. 12 is a plan view with certain parts broken away and certain parts shown in section of the portion of the machine below the head; Fig. 13 is a view in front elevation partly in section illustrating particularly the driving connections for the machine; Fig. 14 is a view partly in side elevation and partly in vertical section of substantially the mechanism shown in Fig. 13; Fig. 15 is a detail sectional view taken substantially on the line 15—15 of Fig. 14; Fig. 16 is a detail sectional view taken substantially on the line 16—16 of Fig. 14; and Fig. 17 is a detail view partly in side elevation and partly in section illustrating a portion of the mechanism shown in Fig. 10.

In the machine illustrated in the drawings the edge setting mechanism is fixed in position as regards the transfer of the point of operation about the work and a shoe supporting jack is provided which is movably supported in the machine to enable the shoe to be moved in the direction of feed to

transfer the point of operation about the shoe, and transversely of the direction of feed to maintain the edge of the shoe sole in the proper lateral relation to the edge setting mechanism and to be tipped and turned to change the position of the shoe with relation to the edge setting mechanism to compensate for the surface and edge curvatures of the shoe sole. The movement 10 of the shoe to transfer the point of operation about the shoe is imparted thereto by devices acting on the jack to impart shoe feeding movements to the jack and the position changing movements are imparted to 15 the shoe by devices acting on the jack to impart tipping and turning movements to the jack. Except as changed and modified in embodying the present invention in a machine adapted to set the edges of shoe 20 soles, the work supporting jack is substantially that disclosed in the pending application filed in my name on December 21, 1918, Serial No. 269,076, while it is moved and controlled in a manner similar to that 25 in the machine shown and described in application Serial No. 355,583, filed February 2, 1920, in the name of Alfred R. Morrill.

The edge setting mechanism of the machine comprises a vibratory carrier 2 (Figs. 30 2, 3 and 4), upon which are mounted the edge setting tools. The carrier 2 is secured to the forward end of a slide 4, mounted for forward and rearward movements in a guideway in a block 6, pivoted on the lower 35 end of a hollow shaft 8 secured in a bracket 10 attached to a carriage 12. The block 6 is held in position on the shaft 8 by means of a bolt 14 (Fig. 5), upon the upper end of which is threaded a nut 16.

40 The block 6 is rapidly oscillated on the shaft 8 during the operation of the machine to impart vibratory or oscillatory movements to the edge setting tools. Oscillatory movements are imparted to the block 6 from a 45 rotary shaft 18 journaled in bearings in the carriage 12 through a pitman 20 pivotally connected at one end with an arm 22 (Fig. 6) on the block 6 and carrying at its other end an eccentric strap 24 surrounding an 50 eccentric 26 formed on the lower end of the shaft. The shaft 18 is driven through intermeshing spiral gears 27 and 28 from a horizontal shaft 30 which constitutes the main shaft of the edge setting head. The main 55 shaft 30 is journaled in bearings formed on the carriage 12 and is driven from an electric motor indicated at 32 secured to said carriage.

Upon the forward end of the carrier 2 is 60 mounted an edge setting tool 34 for operating on the sole edge about the forepart of a shoe and an edge setting tool 36 for operating on the sole edge along the shank. The slide 4 is acted upon by a coiled spring which 65 tends to force the slide forwardly so as to

hold the edge setting tool which is in operation, in yielding contact with the sole edge. To this end a longitudinally movable rod 38 is connected at its forward end by a universal joint with the slide 4 and a coiled 70 spring 40 surrounding the rod is interposed between an adjustable sleeve 42 threaded into the bracket 10 and a collar 44 secured to the rod, the spring tending to force the rod and the slide 4 forwardly. The forward movement of the rod under the action of the spring is limited by a stop collar 46 secured to the rear end of the rod. The force exerted by the spring 40 may be adjusted by 75 adjusting the sleeve 42. 80

To enable a shoe to be located and held in operating position with relation to the edge setting tools, the machine is provided with a work table or guide 48 arranged to engage in the crease between the upper and the projecting margin of the sole of a shoe. The work table is secured to an arm 50 on the frame and is arranged to extend in front of the tool which is in operating position as 85 clearly shown in Figs. 3, 4 and 5. 90

The proper burnishing or setting of the edge of a shoe sole usually requires the use of a different form of setting tool for setting the edge about the forepart of the sole from that which is employed in setting the edge along the shank. In the present machine the setting tool 34 is especially formed for setting the edge about the forepart while the setting tool 36 is especially formed for setting the edge along the shank. To enable 100 the setting tools 34 and 36 to be moved alternatively into position to set the edge of the sole without changing the position of the jacked shoe or while the shoe remains in operating position with the table 48 engaged in the crease between the upper and the projecting margin of the sole, mechanism is provided for adjusting the carrier 2 to shift the position of the forward end of the carrier both in a direction transverse to the plane of 105 the sole and also in a direction toward and from the sole edge. In the illustrated construction the carriage 12 is eccentrically mounted in a bearing in a rotatably adjustable supporting ring 140 which in turn is 110 mounted to rotate in a bearing or raceway formed by the arcuate arms 142 on the frame of the machine. During the adjustment of the ring 140 the carriage 12 is held from turning with the ring and a rotary movement is also imparted to the carriage, the bodily movement given to the carriage by the adjustment of the ring 140 and the rotary 115 adjustment of the carriage producing the required movements of the carrier 2 to shift the edge setting tools. To this end the carriage 12 is pivotally connected at 144 with one end of a pitman 146, to the opposite end of which is secured an eccentric strap 147 120 embracing an eccentric 148 secured to a rock 125

130

shaft 150 mounted on a bearing in the frame. The ring 140 is rotatably adjusted by the rotation of the rock shaft 150 through a connection consisting of an arm 152 secured to the rock shaft and a link 154 connecting said arm with the ring 140. The rock shaft 150 is rotated manually to adjust the carriage 12. The mechanism for rotating the shaft comprises a gear 156 mounted on the shaft and a gear segment 158 secured to a second rock shaft 160 and meshing with the gear 156. An arm 162 is secured to the shaft 160 and is connected by a link 164 with a hand lever 166 pivoted at 168 on the frame.

When the edge setting operation is started along the shank of a shoe the ring 140 is adjusted in the position shown in Fig. 4 and the edge setting tool 36 is located in operating position as shown in this figure. When the forepart of the shoe sole is reached the operator grasps the upper end of the hand lever 166 and swings the same from the position shown in Fig. 4 to the position shown in Fig. 3. This movement of the hand lever turns the ring 140 to adjust bodily the carriage 12 and rotates the eccentric 148 to adjust rotatably said carriage, the combined movements thus imparted to the carriage shifting the carrier first outwardly to disengage the tool 36 from the edge of the sole, then downwardly to bring the tool 34 into a position to engage the sole edge and then forwardly to engage the tool 34 with the sole edge. When the shank of the shoe is reached in setting the edge of the sole on the side of the shoe last operated upon, the hand lever 166 is shifted from the position shown in Fig. 3 back to the position shown in Fig. 4. The carriage 12 will thus be adjusted to impart movements to the carrier 2, reverse to those described above to disengage the tool 34 from the sole edge and to bring the tool 36 back into operating position. The arms 142 may be relatively adjusted by means of an adjusting screw 170 so that they will exert sufficient friction on the ring 140 to hold the same in adjusted position.

The jack for supporting a lasted shoe during the operation of the machine comprises a heel support 52 and a toe rest 54 mounted upon a gyratory spindle 56. It is so constructed and arranged that upon the placing of a shoe on the jack the shoe is automatically located in a predetermined and unvarying position lengthwise of the jack regardless of the size of the shoe placed on the jack and is then securely clamped in adjusted position, and that at the completion of the operation on the shoe the shoe is unclamped and the parts of the jack are restored to their initial positions ready for the application of another shoe to the jack. The shoe is gaged with relation to the jack from the forward point in the bulge in the toe portion of the upper of the shoe, this point

in the shoe being located in a predetermined and unvarying position with relation to the toe rest 54 before the shoe is clamped on the jack.

The lower end of the jack spindle is secured to a hemispherical shell or casing 58 connected by means of a gimbal joint with a wheel 60 journaled on a stud 62. The stud 62 is secured in a casing carried at the forward ends of supporting arms 64, the rear ends of which are secured in a carrier 66 pivoted at 67 to swing vertically on the upper end of a support 68. The support 68 is pivoted at 70 and 72 on a second support 74 to swing laterally of the machine. The support 74 is mounted on pivoted studs 76 to swing forwardly and rearwardly. The jack spindle is yieldingly supported to move vertically about the pivot 67 by means of a coiled spring 78, the strength of the spring being such that it almost counterbalances the weight of the jack, with the supported work, and the associated elements at the outer side of the pivot 67, and the margin of a shoe applied to the jack will rest lightly under the influence of gravity on the table 48. The shoe is held against the table by a spring 79 connected to a pivoted arm 324 which is in turn connected to the jack spindle 56 by a link 322 (Fig. 10).

During the operation of the machine on a shoe, the shoe is held at the point of operation by the engagement of the work table 48 with the welt and adjacent portions of the upper at the crease. Relatively slight vertical movements are imparted to the jack and the shoe by the cooperative action of the spring 78 and the table 48, the table acting as a guide for the shoe. The supporting devices for the jack spindle permit the lower end of the spindle to be freely moved horizontally in any direction and also permit the jack to tip freely in any direction about the lower end of the spindle. Tipping and turning movements are imparted to the shoe to position the shoe properly with relation to the operative edge setting tool as the point of operation is transferred about the shoe. The required tipping movements are imparted to the shoe by devices acting to move the lower end of the jack spindle forwardly and rearwardly and laterally of the machine and the required turning movements are imparted to the shoe by devices acting to rotate the jack spindle. Because of the fact that the shoe is held at all times at the point of operation by the engagement of the table 48 with the crease, the tipping and turning movements imparted to the shoe are caused to take place about said table as a fulcrum.

The support 74 is swung forwardly and rearwardly to impart forward and rearward movements to the lower end of the jack spindle and corresponding tipping movements to the shoe by means of a cam lever 80

pivoted on a shaft 82 and a ball ended link 84 connecting one arm of the lever with the said support. The support 68 is swung laterally of the machine to impart similar movements to the lower end of the jack spindle and to tip the shoe in this direction by means of a cam lever 86 pivoted on the shaft 82 and a link 88 connecting one arm of the cam lever with an arm on said support. The 10 wheel 60 is rotated to impart rotary movements to the jack spindle and lateral turning movements to the shoe by means of a cable 90 passing about the wheel, about the guide pulleys 92 and 94 mounted on the carrier 66 and over a stationary guide pulley 96. One end of the cable is secured to a pulley 98 mounted to rotate on a stud 100 and to the other end of the cable is attached a weight 102. Rotary movements of the pulley 98 are produced and controlled by means of a cam lever 104 pivoted on the shaft 82 and connected to the pulley through a gear segment 106 and a gear 108. Each of the cam levers 80, 86 and 104 carries a cam roll 25 arranged to engage a periphery of one of a series of cam disks mounted on a shaft 110.

The mechanism for actuating the jack to impart feeding movements to the shoe comprises a feeding lever 112 pivoted at 114 on the frame and a link 116 connecting said lever with the toe end of the jack. During the edge setting operation the feeding lever 112 is swung toward the left (Fig. 1) to actuate the jack to advance the marginal portion 30 of the shoe bottom past the operative edge setting tool. The mechanism for actuating the feeding lever comprises an arm 118 pivoted at 120 on the frame and pivotally connected links 122 and 124 connecting the arm 40 118 with the feed lever. The arm 118 is actuated through a link 126 from a cam lever 128 pivoted on the shaft 82 and carrying a cam roll arranged to engage the periphery of a cam disk mounted on the cam shaft 110. 45 The path of the connection between the links 122 and 124 is controlled by an arm 130 pivoted at 132 on a lever 134 hereinafter termed the fulcrum carrying lever which is pivoted at 136 on the frame. During the operation 50 of the machine the fulcrum carrying lever is locked in position. When a shoe is placed in the machine, however, the fulcrum carrying lever is unlocked and is free to be adjusted in accordance with the size of the shoe. The 55 feeding lever 112 and the fulcrum carrying lever are acted upon by a weight 137 attached to a cable 138 connected with said levers which takes up back lash and maintains the cam roll on the lever 128 in contact with the cam disk.

The amplitude of movement imparted to the feed lever 112 is adjusted in accordance with the size of the shoe to be operated upon by the placing of the shoe in position in the 60 machine to start the operation. In changing

from one size of shoe to a smaller size the fulcrum carrying lever 134 is swung to the left while in changing from one size of shoe to a larger size the fulcrum carrying lever is swung to the right. The adjustment of 70 the pivot of the controlling arm 130 produced by the adjustment of the fulcrum carrying lever adjusts the amplitude of movement imparted to the feeding lever for the size of the shoe to be operated upon. 75

In order that the jack actuating feeding mechanism may operate to advance the marginal portion of the shoe bottom past the edge setting device always at the same uniform rate regardless of the size of the shoe, 80 the speed of the cam shaft 110 is adjusted in accordance with the size of the shoe to be operated upon. This constant rate of feed causes a uniform rubbing action of the edge-setting tools for shoes of all sizes, and this, 85 by choosing the proper rate of oscillation of the tools, may be maintained at the most effective degree for finishing the sole-edge. The adjustment of the speed of the cam shaft is effected upon the depression of the 90 starting treadle to start the machine into operation by mechanism controlled from the fulcrum carrying lever.

The mechanism for driving the cam shaft 95 110 comprises a gear 172 secured to the upper end of said shaft and arranged to be driven from a gear 174 formed on the lower end of a sleeve 176 through a train of gears 178, 180, 182, 184, 186 and 188. The sleeve 176 is driven from a shaft 190 through a 100 variable speed ratchet and pawl transmission mechanism indicated as a whole at 192 in Fig. 14.

The shaft 190 is driven from a shaft 194 through a toothed clutch 196. The shaft 194 in turn is driven through intermeshing spiral gears 198 and 200 from the driven member 202 of a friction clutch which constitutes the main driving clutch of the machine. The driving member of the clutch indicated at 204 is secured to the main driving shaft 206. During the operation of the machine the members 202 and 204 of the main driving clutch are engaged and the cam shaft 110 is driven through the connections described at a speed depending upon the adjustment of the ratchet and pawl transmission mechanism 192. The transmission mechanism 192 is controlled by means of an adjustable ring 208 pivoted at 210 on the frame. The position of the ring is controlled from a longitudinally movable controller bar 212 through connections comprising an arm 213, a rock shaft 214, and an arm 215. The left hand end of the controller bar 212 (Fig. 12) is movably supported by a lever 216 and a link 217 and is formed with oppositely inclined surfaces 218 leading to a recess 220 adapted to receive a roll 222 mounted on the fulcrum car- 120 125 130

trying lever 134. When the machine is at rest the controller bar 212 is held in its rearward position by the action of a spring 224 as shown in Fig. 12. Upon the depression 5 of the starting treadle the controller bar is swung forward to engage the roll 222 in the recess 220 by means of one or more pins 226 mounted on a longitudinally movable bar 228 and arranged to engage 10 the lever 216.

The bar 228 is mounted to slide longitudinally in suitable guides, and the left hand end thereof is connected by a link 230, a bell crank lever 232 and a treadle rod 234 15 with a pivoted starting treadle 236. The starting treadle is normally held in elevated position by means of a coiled spring 238. Through the connections described, upon the depression of the treadle the bar 228 is 20 moved longitudinally to the right (Fig. 12), this movement of the bar operating to cause the engagement of the members 202 and 204 of the main driving clutch to start the machine in the manner hereinafter described. After the machine is started the treadle is released and is moved upwardly 25 by the action of the spring 238, and the bar 228 is moved back to its normal position. During the movement of the bar to the 30 right the lever 216 is actuated to swing the controller bar 212 forwardly.

Before the depression of the treadle a shoe 35 is placed in the machine in the correct position for the starting of the edge setting operation, thereby adjusting the fulcrum carrying lever 134 in accordance with the size of the shoe. When the controller bar 212 is swung forwardly, through the engagement of the bar with the roll 222, the 40 bar is adjusted longitudinally in a position corresponding with the position of the fulcrum carrying lever 134, and through the connections described, the ring 208 is adjusted to adjust the speed of the cam shaft 45 110 in accordance with the size of the shoe to be operated upon.

The mechanism for locking the fulcrum carrying lever 134 in position during the 50 operation comprises a rod 240 and devices for locking the rod from longitudinal movement indicated as a whole at 242. These locking devices are actuated through suitable connections from the controller bar 212 to lock and release the rod 240 respectively 55 during the forward and rearward movements of the controller bar.

The controller bar is held in forward position during the operation on a shoe by 60 means of a spring actuated pivoted latch 244, which, as the controller bar is swung forwardly engages a projection on the lever 216 and holds the lever in position when the bar 228 returns to its initial position upon the release of the treadle. Upon the placing 65 of another shoe on the jack, the latch

244 is thrown out allowing the controller bar to swing back to its rearward position.

The edge setting tools are driven continuously from the electric motor 32. After a shoe has been placed on the jack and has 70 been adjusted in a predetermined position with relation to the jack and clamped in adjusted position automatically by the action of the jack mechanism, the operator effects engagement between the table 48 and the crease between the upper and the welt at the proper point for the starting of the edge setting operation and then depresses the treadle 236 to engage the main driving clutch to start the machine into operation. 75 When the point on the shoe has been reached at which the operation is to be stopped, the members of the main driving clutch are disengaged and the rotation of the driven member 202 of the clutch is arrested by automatically acting devices. This occurs when the end of the shank on the side of the shoe first operated upon is 80 reached and again at the end of the fore-part to enable the edge setting tools to be 85 interchanged at these points and also occurs at the completion of the operation on the shoe.

The driving clutch member 202 is carried by a sleeve 246 mounted to rotate and to 90 slide longitudinally on the driving shaft 206 and also carrying a brake member 248 arranged to engage a fixed brake shoe 250. The sleeve is normally held in its upper position with the members of the main driving 100 clutch engaged and with the members of the brake disengaged by means of a coiled spring 252.

The mechanism for moving the sleeve 246 downwardly to disengage the clutch and engage the brake comprises a bell crank lever 254 pivoted at 256, one arm of which carries a cam roll 258 engaging in a cam groove 260 in the sleeve. A locking pin 262 is mounted to slide longitudinally in a carrier 264 and is 110 arranged to engage in a recess 266 in the other arm of the bell crank lever, Fig. 15. The carrier 264 is mounted to slide longitudinally in suitable guides and is acted upon by a coiled spring 268 which normally holds 115 the carrier in position with a shoulder on the carrier in engagement with the inner end of a screw threaded sleeve 270. The locking pin 262 is acted upon by a coiled spring 272 which tends to move the same into engagement with the bell crank lever 254. During 120

the normal operation of the machine, however, the locking pin is held out of engagement with the bell crank lever so that the lever is oscillated idly. In stopping the machine the locking pin is released and is engaged in the recess in the bell crank lever thus locking the lever to the carrier 264. The locking of the lever to the carrier by the locking pin preferably occurs when the cam roll 125 130

- 258 is in the upper idle portion of the cam groove 260, and as the cam roll thereafter reaches a downward throw in the cam groove the bell crank lever is swung in a direction to 5 move the carrier longitudinally to the right (Fig. 15). The cam roll then passes into the lower idle portion of the cam groove and finally engages in an upward throw in the cam groove. When this occurs the sleeve 246 is moved downwardly to disengage the main driving clutch and engage the brake. In order to render this upward throw in the cam groove effective to move the sleeve downwardly, a latch lever 274 is provided to engage the carrier 264 and prevent the return of the carrier to its normal limiting position after it is moved longitudinally to the right. The latch lever is normally held in lowered position and is acted upon by a coiled spring 276 which tends to swing the same upwardly into acting position. As the carrier 264 is moved to the right the latch lever is swung upwardly into the position shown in Fig. 13 and as the carrier moves back to the left during the passage of the cam roll through the upward throw in the cam groove 260 the latch lever arrests the return movement of said carrier before it reaches its normal limiting position. Upon the stopping of the return movement of the carrier the sleeve 246 is moved downwardly to disengage the clutch and engage the brake.
- 30 The locking pin 262 is normally held in retracted position by means of a bell crank lever 277 connected through intermeshing gear segments with a lever 278. The lever 278 is pivotally connected by means of a pin 280 with the upper end of a vertically movable rod 282. This rod also controls the position of the latch lever 274 through the engagement of the rear end of the pin 280 in the slot in the latch lever. In starting the machine the rod 282 is depressed by the operator, and in stopping the machine the rod 45 is released and is then moved upwardly by the action of a coiled spring 284. When the rod is depressed the locking pin is disengaged from the bell crank lever 254 thereby releasing the sleeve 246 and the latch lever 274 is moved downwardly out of acting position, thereby releasing the carrier 264. The release of the rod 282 and the upward movement thereof on stopping the machine releases the locking pin and the latch lever.
- 50 The rod 282 is pivotally connected with a second vertically movable rod 286 arranged to be actuated by a lever 288. The lever 288 is engaged by the right hand end of the bar 228 as said bar is moved to the right (Figs. 12 and 13) by the depression of the treadle and the lever is thereby actuated to depress the rods 286 and 282. The rods are held in depressed position by means of a slidably mounted spring pressed latch 290 arranged to engage a projection on the rod 286. The

stopping devices are thus held out of operation by the latch 290 after the starting of the machine allowing the treadle to be released and the bar 228 to be moved back to its normal position.

50 In stopping the machine the latch 290 is automatically disengaged from the projection on the rod 286 allowing the stopping devices to be thrown into operation. The latch is controlled from a lever 292 through the engagement of a pin 294 mounted on one end of the lever in a V-shaped slot in the latch. In stopping the machine the left hand end of the lever 292 (Figs. 13 and 16) is swung forwardly by automatically acting 80 devices thereby retracting the latch.

The mechanism for swinging the lever 292 forwardly to stop the machine comprises a lever 296 (Fig. 12) pivoted at 298 on a bell crank lever 300, and a link 302 connecting the lever 296 with the lever 292. When the end of the shank on the side of the shoe first operated upon is reached in the edge setting operation, the right hand end of the lever 296 is engaged by a projection 304 on a plate 306 adjustably secured to the gear 172 and is swung rearwardly thereby actuating the lever 292 to stop the machine. In a similar manner when the end of the forepart of the shoe is reached, the right hand end of the lever 296 is engaged by a projection 308 formed on a plate 310 secured to the gear 172 thereby actuating the lever 296 and the lever 292 to stop the machine. The lever 296 is actuated in a similar manner to 100 stop the machine at the completion of the edge setting operation by the engagement of a block 312 secured to the gear 172 with the right hand end of said lever.

105 When the machine is stopped at the completion of the edge setting operation, the jack is swung forwardly out of operating position and is held in forward position during the turning movement imparted thereto to restore the same to its initial position. The mechanism for swinging the jack forwardly out of operating position comprises a lever 314 (Fig. 17) mounted to turn loosely on a rock shaft 316, and a slide 318 mounted in the lever 314 and arranged to engage a projection 320 formed on a bar 322 connected at its forward end with the jack and supported at its rear end by a pivoted arm 324. During the normal operation of the machine, the lever 314 is held in its rearward position, as shown in Fig. 12. Upon stopping the machine the lever 314 is swung forwardly into the position shown in Figs. 10 and 17. During this movement of the lever 314, the slide 318 engages the projection on the bar 322 and the bar is actuated to swing the jack forwardly out of operating position.

115 The mechanism for actuating the lever 314 comprises a rock shaft 326, an arm 328

secured to the rock shaft and carrying a gear segment 330, a cooperating gear segment 332 secured to the rock shaft 316, a pin 334 mounted in the gear segment 332 and arranged to engage the lever 314 to swing the same forwardly and a spring 336 connecting the lever 314 with the rock shaft 316. The rock shaft 326 is actuated through a rock shaft 338 (Figs. 13 and 14), a block 340, an arm 342, a pitman 344 and an eccentric strap 346 from an intermittently rotating eccentric 348.

Upon stopping the machine the eccentric 348 is thrown into operation, and after executing a complete revolution is thrown out of operation. During the first half revolution of the eccentric, the lever 314 is swung into its forward position through the engagement of the pin 334 with the lever. The lever is held from return movement during the last half revolution of the eccentric by means of a spring pressed latch 350. Through the action of this latch on the lever 314, the jack is held in forward position during the turning movement imparted to the jack to restore the same to normal position and during the removal of the shoe from the jack. The latch is thrown out, however, when another shoe is placed on the jack allowing the lever 314 to swing back to its rearward position under the action of the spring 336. As a shoe is placed on the jack a sharp downward blow is delivered to the shoe to seat the last pin in a hole in the last so as to trip the jack. This forces the shoe and jack downwardly. The downward movement imparted to the jack depresses the slide 318 which is connected with the latch by a rod 352 and the latch is thereby thrown out.

The latch 244 is thrown out to release the controller bar 212 by the swinging movement of the lever 314 from its forward to its rearward position through the engagement with the latch of a spring pressed plunger 354 mounted in the lever. As the latch is thrown out the controller bar 212 is swung back to its rearward position and the locking devices for the fulcrum carrying lever 314 are actuated to unlock said lever.

The driving mechanism for the eccentric 348 comprises a shaft 356 (Figs. 13 and 15) which is driven from the main driving shaft 206 at a relatively slow speed through gears 358, 360, 362 and 364. A clutch member 366 is splined to the shaft 356 and is arranged to engage a corresponding clutch member 368 upon the eccentric. The position of the clutch member 366 on the shaft 356 is controlled by means of a lever 370 (Fig. 16) pivoted on a shaft 372 and normally held in position with the clutch member 366 disengaged from the clutch member 368, as shown in Fig. 13 by means of a spring pressed detent pin 374. Upon stopping the machine

the lever 370 is actuated to move the clutch member 366 upwardly into engagement with the clutch member 368.

The mechanism for thus actuating the lever 370 comprises a rod 376 pivotally supported upon an arm 378 secured to one end of a rock shaft 380. To the other end of the rock shaft is secured an arm 382 connected through intermeshing gear segments with one arm of a bell crank lever 384 pivoted at 386. The other arm of the bell crank lever carries rolls engaging between the flanges on a sleeve 388 mounted on the locking pin carrier 264 of the clutch-disengaging mechanism intermediate the spring 268 and a stop nut on the outer end of the carrier. Through the connections described as the carrier is moved to the right (Fig. 13) upon stopping the machine, the rod 376 is lifted and as the carrier moves back to the left the rod is depressed. The rod is formed with a projection 390 which is normally located behind a projection 392 on the forward end of the lever 370, as shown in Fig. 14. The lower end of the rod engages between two pins 394 mounted on a lever 396 pivoted co-axially with the lever 292 and normally held in central position with relation to the lever 292 by means of spring pressed plungers 398. As stated above, in stopping the machine at the completion of the operation on the shoe the left hand end of the lever 292 is swung forwardly, and during this movement of the lever 292 the rod 376 and the lever 396 are held from forward movement by the engagement of the projection 390 with the projection 392. As the rod is lifted by the movement of the carrier 264 the projection 390 is carried above the projection 392 and the lever 396 and the rod are then swung forwardly by the action of one of the spring pressed plungers 398, thereby locating the projection 390 above the projection 392. Then as the rod is depressed by the movement of the carrier 264 the lever 370 is actuated to engage the clutch member 366 with the clutch member 368. Through the engagement of these clutch members the eccentric 348 is driven through a complete revolution before the machine finally comes to rest.

As the eccentric completes a single revolution the lever 396 and the rod 376 are swung rearwardly to disengage the projection 390 from above the projection 392, and the lever 370 is then moved back to its normal position by the action of the pin 374, thereby moving the clutch member 366 downwardly out of engagement with the clutch member 368. The mechanism for thus swinging the lever 396 rearwardly comprises a lever 400 (Fig. 16) pivoted at 402 and connected with the lever 396 through intermeshing gear teeth. The lever 400 carries a pivoted dog 404 having a projection arranged to be engaged by

a stud 406 mounted on an arm 408 secured to the rock shaft 326. The dog 404 has a limited pivotal movement with relation to the lever 400 and is normally held by a 5 spring in engagement with a stop formed on the lever in the position shown in Fig. 16. When the lever 396 is swung forwardly the projection on the dog 404 is carried into position to be engaged by the stud 406. As the 10 arm 408 is swung to the left during the first half revolution of the eccentric, the stud 406 engages the projection on the dog and swings the dog until the stud passes by the projection. As the arm 408 swings back to the 15 right during the last half revolution of the eccentric the stud 406 again engages the projection on the dog. The engagement of the dog with the stop on the lever 400 prevents the dog from swinging under the action of 20 the stud and the lever 400 is actuated to swing the lever 396 rearwardly to its normal position. This movement of the lever 396 swings the rod 376 rearwardly, thereby 25 disengaging the projection 390 from the projection 392.

From an inspection of Fig. 12 it will be noted that the projection 304 and the projection 308 are so constructed that these projections, when engaged with the lever 296, will 30 remain in engagement with the lever only during a very small part of a rotation of the gear 172. After one of these projections has engaged the lever 296, it almost immediately frees said lever, allowing it and the 35 lever 292 to swing back to their normal positions before the lever 370 is actuated by the rod 376 to engage the eccentric actuating clutch. The eccentric therefore will not be thrown into operation when the machine 40 is stopped, as the end of the shank on the side of the shoe first operated upon or the end of the forepart of the shoe is reached. The block 312, however, is so constructed that the right hand end of the lever 296 45 when engaged by the block is held in rearward position during a considerable part of a rotation of the gear 172. In stopping the machine at the completion of the operation therefore, the left hand end of the lever 292 is held in forward position until the lever 50 370 is actuated by the rod 376 to engage the eccentric actuating clutch. Thus the jack remains in its rearward or operating position with the table 48 engaged in the crease 55 between the welt and upper of the shoe when the machine is stopped at the completion of the operation on the side of the shank first acted upon and on the forepart and the jack is swung forwardly out of operating position when the machine is stopped at the completion of the operation on the shoe.

During the operation of the machine on the shoe the cam shaft 110 is driven through the greater part of a revolution, and after 60 the main driving clutch has been disengaged

the cam shaft is driven in the same direction as during the normal operation of the machine through the remaining part of a revolution to bring the same to its initial or starting position. During this movement 7 of the cam shaft, after the operation on the shoe has been completed, the jack is turned through half a revolution in a direction opposite to the direction in which it is turned during the normal operation to bring the 7 jack to its initial or starting position. The cam shaft is rotated through the remaining part of a revolution after the disengagement 8 of the main clutch by the endwise movement of the lever 296 imparted thereto by the movement of the bell crank lever 300.

The bell crank lever 300 is pivoted at 410 and is connected by a link 412 with the arm 328. As the arm 328 is swung forwardly 8 (Fig. 12), the lever 296 is carried to the left beyond the projecting portion of the contact block 312 by the movement of the bell crank lever 300, and as the arm 328 is swung back rearwardly the lever 296 is carried to the right by the movement of the bell crank. By the engagement of the end of the lever 296 with an abutment or shoulder formed on the projecting portion of the contact block 312 during this latter movement of the lever, the gear 172 and the cam shaft are turned through the remaining part 9 of a revolution to bring the same to starting position.

Having explained the nature and object 1 of the invention, and having specifically described a machine embodying the invention in its preferred form, what is claimed is:—

1. An edge setting machine having, in combination, two edge setting tools, means for actuating the tools, a shoe supporting jack, mechanism for changing the relative positions of the shoe and the operative tool to compensate for the surface and edge curvatures of the shoe sole as the point of operation is transferred about the shoe, and means for relatively moving the tools and the jack to locate the tools interchangeably in operating position with relation to the sole of a shoe supported on the jack.

2. An edge setting machine having, in combination, two edge setting tools, means for actuating the tools, a shoe supporting jack, mechanism for changing the relative positions of the shoe and the operative tool to compensate for the surface and edge curvatures of the shoe sole as the point of operation is transferred about the shoe, and means for moving the tools to locate the same interchangeably in operating position with relation to the sole of a shoe supported on the jack.

3. An edge setting machine having, in combination, an oscillatory tool carrier, means for oscillating the carrier, two edge

setting tools of different forms mounted on the carrier, a shoe supporting jack, mechanism for changing the relative position of the shoe and the operative tool to present the shoe properly to the tool as the point of operation is transferred about the shoe, and means for adjusting the carrier to locate the tools interchangeably in operating position relatively to the sole of a shoe supported on the jack.

4. An edge setting machine having, in combination, two edge setting tools of different forms, a shoe supporting jack, mechanism for changing the relative positions of the shoe and the operative tool to present the shoe properly to the tool as the point of operation is transferred about the shoe, and means for shifting the tools in a direction perpendicular to the plane of the sole of a shoe supported on the jack, and also in a direction parallel with said plane toward and from the central portion of the sole to locate the tools interchangeably in operating position with relation to the sole edge.

5. An edge setting machine having, in combination, an oscillatory tool carrier, means for oscillating the carrier, two edge setting tools of different forms mounted on the carrier, a shoe supporting jack, mechanism for changing the relative positions of the shoe and the operative tool to present the shoe properly to the tool as the point of operation is transferred about the shoe, and means for adjusting the carrier to shift the tools in a direction perpendicular to the plane of the sole of a shoe supported on the jack, and also in a direction parallel with said plane toward and from the central portion of the sole to locate the tools interchangeably in operating position with relation to the sole edge.

6. An edge setting machine having, in combination, a yieldingly mounted edge setting tool, means for actuating the tool, and a fixed work guide arranged to engage in the crease between the upper and the projecting margin of the sole of a shoe.

7. An edge setting machine having, in combination, two edge setting tools, a fixed work guide determining the operating position of the shoe in contact with which the shoe is moved to transfer the point of operation of a tool along the sole edge, and means for moving the tools interchangeably into operating position.

8. An edge setting machine having, in combination, two edge setting tools, a fixed work guide determining the operative position of the shoe, and means for moving the tools in a direction perpendicular to the plane of the sole of a shoe being operated upon, and also in a direction parallel with said plane toward and from the central portion of the sole to locate the tools inter-

changeably in operating position with relation to the sole edge.

9. An edge setting machine having, in combination, a yieldingly mounted vibratory edge setting tool, means for vibrating the tool, and a fixed work guide extending in front of the tool and arranged to engage in the crease between the upper and the projecting margin of the sole of a shoe.

10. An edge setting machine having, in combination, an edge setting tool, means for actuating the tool, a guide for engagement in the crease between the upper and the projecting margin of the sole of a shoe to locate the shoe with relation to the tool, a freely movable shoe supporting jack, means acting yieldingly to maintain the shoe in position with the guide engaged in said crease, and mechanism for actuating the jack to tip the shoe about said guide as a fulcrum and thereby position the shoe with relation to the tool as the point of operation is transferred about the shoe.

11. An edge setting machine having, in combination, a rotary actuating shaft, an adjustable carriage for the shaft, an oscillatory tool carrier pivoted on the carriage, two edge setting tools mounted on the carrier, connections for oscillating the carrier from the shaft, and means for adjusting the carriage to locate the tools interchangeably in operating position comprising a ring in which the carriage is eccentrically mounted to turn relatively to the ring, bearings in which the ring is rotatably adjustable, and means for controlling the turning movement of the carriage during the adjustment of the ring.

12. An edge setting machine having, in combination, a rotary actuating shaft, an adjustable carriage for the shaft, an oscillatory tool carrier pivoted on the carriage, two edge setting tools mounted on the carrier, connections for oscillating the carrier from the shaft, and means for adjusting the carriage to locate the tools interchangeably in operating position comprising a ring in which the carriage is eccentrically mounted to turn relatively to the ring, bearings in which the ring is rotatably adjustable, and means for causing rotary movement of the carriage during the adjustment of the ring.

13. An edge setting machine having, in combination, a vibratory tool carrier, an edge setting tool mounted on the carrier, means for vibrating the carrier, a guide for engagement in the crease between the upper and the projecting margin of the sole of a shoe arranged to extend in front of the edge setting tool, a freely movable shoe supporting jack, means acting yieldingly to maintain the shoe in position with the guide engaged in said crease, and mechanism for

actuating the jack to tip the shoe about said guide as a fulcrum as the point of operation is transferred about the shoe.

14. A machine for operating upon shoes having, in combination, an adjustable carriage, a tool carrier mounted on the carriage, mechanism for adjusting the carriage to locate tools mounted in the tool carrier interchangeably in operating position comprising a ring in which the carriage is eccentrically mounted to turn relatively to the ring, bearings in which the ring is rotatably adjustable, a rock shaft, an arm on the rock shaft, a link connecting said arm with

10 15 the ring, an eccentric carried by the rock shaft, a link connected at one end for actuation from said eccentric and pivotally connected at its outer end with the carriage, and means for turning the rock shaft to 20 adjust the ring and the carriage.

15. A machine for operating upon shoes, having in combination, a shoe supporting jack, a tool arranged to operate about a shoe, mechanism for changing the relative 25 positions of the shoe and tool to present the shoe properly to the tool as the point of operation is transferred about the shoe, mechanism for stopping the machine with the jack in operative position at one or more 30 predetermined points before the completion of the operation, and means for stopping the machine at the completion of the operation and moving the jack forwardly out of operating position.

35 16. A machine for operating upon shoes having, in combination, means for operating upon a shoe, a shoe supporting jack, mechanism for changing the relative position of the shoe and the operating means 40 to present the shoe properly to the tool as the point of operation is transferred about the shoe, and means for stopping the machine with the jack left in operative position at the completion of the operation on 45 the shank on the side of the shoe first operated upon and at the completion of the operation on the forepart, and means for stopping the machine at the completion of the operation upon the shoe and moving the 50 jack forwardly out of operating position.

55 17. An edge setting machine having, in combination, an adjustable carriage, a tool carrier mounted on the carriage, two tools mounted on the carrier, and means for adjusting the carriage to locate the tools interchangeably in operating position comprising a ring in which the carriage is eccentrically mounted to turn relatively to the ring, bearings in which the ring is rotatably 60 adjustable, means arranged to be actuated to rotate the ring, and a connection actuated by said means to rotate the carriage during the rotation of the ring.

65 18. A machine for operating on the edge of the sole of a lasted shoe having, in com-

bination, a shoe supporting jack, a tool for operating on the sole edge, mechanism for changing the relative positions of the shoe and tool to present the shoe properly to the tool as the point of operation is transferred along the shoe, mechanism for stopping the machine at one or more predetermined points in the travel of the tool along the shoe and for stopping the machine at the completion of said travel, and mechanism inactive during the intermediate stop or stops and rendered active upon the final stopping of the machine to move the jack away from operative relation to the tool.

19. A machine for operating on the edge 80 of the sole of a lasted shoe having, in combination, an edge setting tool for operating on the sole edge, a freely movable shoe supporting jack, a guide for engagement in the crease between the upper and the projecting margin of the sole of the shoe carried by the jack, means acting on the jack to yieldingly hold the shoe in engagement with the guide, mechanism for moving the jack to feed the shoe, and mechanism acting on the jack 85 during its feed to tip it about the guide as a fulcrum to maintain the edge of the sole in proper relation to the tool.

20. A machine for operating on the edge 95 of the sole of a lasted shoe having, in combination, two edge setting tools movable alternately into position to act on the sole edge, a freely movable shoe supporting jack, a guide for engagement in the crease between 100 the upper and the projecting margin of the sole of the shoe carried by the jack, means acting on the jack to yieldingly hold the shoe in engagement with the guide, mechanism for moving the jack to feed the shoe, mechanism acting on the jack during its feed to tip it about the guide as a fulcrum 105 to maintain the edge of the sole in proper relation to the tool, and mechanism acting to stop the machine at one or more intermediate points in the feed of the jack to 110 permit shifting of the tools.

21. An edge setting machine having, in combination, an edge setting tool, means for actuating the tool, a fixed work guide arranged to engage the crease between the upper and projecting margin of the sole of the shoe, and automatic means for feeding the shoe and maintaining it in engagement with the guide.

22. An edge setting machine having, in combination, an edge setting tool, means for actuating the tool, a fixed work guide arranged to engage in the crease between the upper and projecting margin of the sole, means for feeding the shoe, and mechanism for controlling its movements to maintain the guide in the crease during the feed.

23. In an edge-setting machine, a shoe-support, a carrier, a plurality of edge-setting tools mounted upon the carrier and having

their operating faces situated adjacent to one another in proximity to the sole-edge of a supported shoe, and mechanism acting when actuated to move the carrier transversely of the sole-edge and toward and from said edge to bring one or another of the setting tools into operative position.

24. In an edge-setting machine, an edge-setting tool, and an eccentric-mounting for the tool movable to vary the relation between the setting tool and the work.

25. In an edge-setting machine, a carriage, a plurality of edge-setting tools mounted upon the carriage, and an eccentric-mounting for the carriage movable to bring one or another of the setting tools into operative position.

26. In an edge-setting machine, a plurality of oscillatory edge-setting tools mounted upon a carriage, the mounting being movable to bring one or another of the setting tools into operative position, and a motor mounted upon the carriage for oscillating the tools.

27. In an edge-setting machine, a carriage, a plurality of edge-setting tools mounted upon the carriage, an eccentric-mounting for the carriage movable to bring one or another of the setting tools into operative position, and a motor mounted upon the carriage for operating the tools.

28. In an edge-setting machine, a jack, a jack-support mounted for universal movement, a guide for engagement with a jacked shoe and serving as a fulcrum during the universal movement of the support, and an edge-setting tool for contact with the sole-edge of the shoe.

29. In an edge-setting machine, a gyroscopic spindle, a jack mounted thereon, a fixed guide for contact with a jacked shoe in the gyration of the spindle, and an edge-setting tool in contact with which the sole-edge of the jacked shoe is moved by the spindle in its gyration.

30. In an edge-setting machine, a gyroscopic spindle, a jack mounted thereon, a fixed guide for contact with a jacked shoe in the gyration of the spindle, yieldable means for maintaining such contact, and an edge-setting tool in contact with which the sole-edge of the jacked shoe is moved by the spindle in its gyration.

31. In an edge-setting machine, a jack, a jack-support mounted for universal movement, a guide for engagement with a jacked shoe and serving as a fulcrum, means for imparting to the support a predetermined movement about said fulcrum, and an edge-setting tool contacting with the sole-edge of the jacked shoe during this movement of the support.

32. In a machine for operating upon shoes, a shoe-support, an operating tool, means for

changing the operation of the tool at certain points in such operation and for relatively separating the tool and supported shoe, and means for changing the operation of the tool at other points and for relatively separating the tool and shoe to a different extent.

33. In a machine for operating upon shoes, a shoe-support, an operating tool, means for stopping the operation of the tool at certain points in such operation and for relatively separating the tool and supported shoe, and means for stopping the operation of the tool at other points and for relatively separating the tool and shoe to a different extent.

34. In a machine for operating upon shoes, a shoe-support, an operating tool, means for stopping the operation of the tool at certain points in such operation and for relatively separating the tool and supported shoe, and means for stopping the operation of the tool at other points and for relatively separating the tool and shoe to a greater extent.

35. In a machine for operating upon shoes, a shoe-support, an operating tool, means for moving the tool away from the supported shoe at certain points in its operation, and means for moving the support away from the tool at other points.

36. In a machine for operating upon shoes, a shoe-support, an operating tool, means for stopping the operation of the tool and moving it away from the supported shoe at certain points in its operation, and means for stopping the operation of the tool and moving the support away from the tool at other points.

37. In a machine for operating upon shoes, a shoe-support, a plurality of operating tools, means for moving the support to change the point of operation of the tools about the supported shoe, means for bringing different tools into action at different points in the movement, and means for moving the support to carry the shoe away from the tools at the end of the operation.

38. In an edge-setting machine, a jack, two edge-setting tools mounted for oscillation together, means for stopping the machine with the jack remaining in operating position, means for shifting the tools to bring one or the other into operative relation with the sole-edge of a jacked shoe, means for stopping the machine, and means for moving the jack away from the tools.

39. In a machine for operating upon shoes, a support arranged to receive shoes of different sizes, an edge setting tool for operating upon a supported shoe, means for feeding the shoe and tool relatively to vary the point of operation, means for oscillating the tool in the direction of feed, and

means for varying the feed to maintain constant the rate of movement at the point of operation for shoes of different sizes.

40. In an edge-setting machine, a movable jack arranged to receive shoes of different sizes, an edge setting tool for operating upon the sole-edge of a supported shoe, means for moving the jack to carry the sole-edge along the tool, and means for controlling the movement of the jack to maintain constant the rate of travel of the sole-edge for shoes of different sizes.

41. In an edge-setting machine, a movable jack arranged to receive shoes of different sizes, an edge setting tool for operating upon the sole-edge of a supported shoe, means for moving the jack to carry the sole-edge along the tool, and means made effective in the application of the shoe to the jack for varying the movement of said jack to maintain constant the rate of travel of the sole-edge for shoes of different sizes.

42. An edge-setting machine having, in combination, a forepart edge-setting tool, a shank edge-setting tool, a shoe supporting jack, means for relatively moving the tools and jack to locate the tools interchangeably in operating position with relation to the sole of a shoe supported on the jack, and mechanism acting automatically while the shank tool is operative to transfer the point of operation along the shank of the sole, while the forepart tool is operative to transfer the point of operation about the forepart of the sole from the shank portion on one side to the shank portion on the other side and at the ends of the shank and forepart to stop the transfer.

43. An edge-setting machine having, in combination, two edge-setting tools, a shoe supporting jack movable to transfer the point of operation of a tool along the sole edge of a shoe supported on the jack, a guide in contact with which the shoe is moved to transfer the point of operation along the sole edge and which determines the position of the shoe transversely of the direction of feed, and means for moving the tools interchangeably into operative position.

44. An edge-setting machine having, in combination, an edge-setting tool, a shoe supporting jack movable to transfer the point of operation of the tool along the sole edge of a shoe supported on the jack, means for vibrating the tool in a fixed plane while maintaining its working face at a constant angle to said plane, and automatic means

for moving the jack to maintain the shoe and the tool in the proper relative positions at the point of operation as such point is transferred along the sole edge.

45. An edge-setting machine having, in combination, a shoe supporting jack, an edge-setting tool, means for moving the jack to transfer the point of operation of the tool along the sole edge of a shoe supported on the jack and a guide in contact with which the shoe is moved and which determines the position of the shoe transversely of the direction of feed.

46. An edge setting machine having, in combination, a yieldingly mounted edge setting tool, means for actuating the tool, and a guide mounted independently of the tool in its yield and which determines the position of the shoe transversely of the direction of feed, in contact with which guide the shoe is moved to transfer the point of operation of the tool along the sole edge.

47. A machine for operating on shoes having, in combination, two operating tools arranged to act successively along different parts of the bottom margin of a shoe, a shoe supporting jack, means for relatively moving the jack and tools to transfer the point of operation about the shoe, mechanism for moving relatively the jack and tools to locate the tools interchangeably in operating position, means acting automatically to stop the relative travel of the tools and jack at one or more points on the shoe where the interchange of tools is to be made, and means acting automatically to move the jack away from operative relation to the tools at the completion of the operation on the shoe.

48. An edge setting machine having, in combination, an edge setting tool, means for vibrating the tool in the direction of feed, and a work guide in contact with which the shoe is moved to transfer the point of operation of the tool along the sole edge arranged to enter the crease between the upper and the projecting margin of the shoe sole and determine the position of the shoe transversely of the direction of feed.

49. An edge setting machine having, in combination, an edge setting tool, means for vibrating the tool in the direction of feed, and a guide in contact with which the shoe is moved and which determines the position of the shoe transversely of the direction of feed.

LAURENCE E. TOPHAM.
